UNITED STATES PATENT OFFICE.

JOSEPH F. BUHR, OF DETROIT, MICHIGAN.

DRILL HEAD FOR DRILLING MACHINES.

Application filed July 5, 1917. Serial No. 178,538.

To all whom it may concern:

Be it known that I, JOSEPH F. BUHR, a citizen of the United States of America, residing at Detroit, in the county of Wayne 5 and State of Michigan, have invented certain new and useful Improvements in Drill Heads for Drilling Machines, of which the following is a specification, reference being had therein to the accompanying drawings.

10 This invention relates to a drill head for drilling machines and has special reference to certain improvements in connection with that type of drill head disclosed by my Patent No. 1,287,017 granted Aug. 14, 1917.

15 In this patent there is disclosed a multiple drill head that may be bodily adjusted in lateral and vertical planes relative to a piece of work, and the present invention aims to provide this multiple drill 20 head by providing novel enclosed means that permits of end drills being simultaneously adjusted, in a lateral plane, relative to a center drill. Furthermore the present invention aims to include novel thrust and 25 anti-frictional bearings which insures ease of operation of the drill and ease of adjustment by an artisan.

The present invention also includes certain other features that will hereinafter 30 appear, and reference will now be had to the drawings, wherein—

Figure 1 is a vertical sectional view of the multiple drill head, with the attaching member partly broken away;

35 Fig. 2 is a side elevation of the complete drill head;

Fig. 3 is a plan of the same;

Fig. 4 is a horizontal sectional view of the drill head taken on the line IV—IV of 40 Fig. 2;

Fig. 5 is a bottom plan of the drill head;

Fig. 6 is a detail view of a clamping member;

Fig. 7 is a horizontal sectional view taken 45 on the line VII—VII of Fig. 2, and

Fig. 8 is a plan of a bolt lock.

In the drawings, the reference numeral 5 denotes an attaching member providing clearance for the spindle of a drilling machine to permit of vertical adjustment in 50 connection with the drill head.

The lower end of the attaching member 5 has an annular flange 6 engaged by a collar 7 secured by screw bolts 1 to the top of 55 a housing cap 8 attached to a housing 9 by screw bolts 10 or other fastening means.

By loosening the screw bolts 1 the housing cap and its housing can be swung in a horizontal plane and adjusted relative to the flange 6 of the attaching member 5.

60 The cap 8 has a central opening 13 providing clearance for a coupling member 4 having a shank or spindle 3 and surrounding the opening 13 is an upstanding flange 14. Seated on the flange 14 is an antifrictional bearing 15 which supports the coupling member 4 by engaging a collar 16 on said coupling member. The coupling member 4 extends through the cap 8 into the housing 9 and fixed on said coupling member is the 65 hub portion 17 of a main gear 18. An anti-frictional bearing 19 is interposed between the hub of the gear wheel 18 and the inside of the flange 14 of the cap, and a gear wheel 21 is loosely mounted on the hub portion 70 17 in the bottom of the housing 9. The anti-frictional bearing 19 is on the hub portion 17 of the gear wheel 18 and serves as an end thrust bearing.

75 The bottom of the housing 9 has a central opening 22 and end openings 23. Extending into the end openings 23 are the upper ends 24 of casings 25 and keyed upon the inner ends of said casings are gears 26 meshing with the gear 21, so that when 80 either of the casings is adjusted or swung in a horizontal plane a similar movement is imparted to the other casing. In other words, the end casings may be simultaneously adjusted by simply manipulating one 85 of the casings and this is an important feature of the present invention. Vertical displacement of the end casings is prevented by tie rods or bolts 27 extending through the cap 8 and provided with heads 28 keyed 90 or otherwise fixed as at 29, in supporting members 20 seated in the cap 8. Loose on each of the bolts 27 are coupled gear wheels 30 and 31, the gear wheels 30 being mounted on extended hubs 31a of the gear wheels 100 31. These gear wheels are supported by anti-frictional bearings 32 and 34 with the gear wheels 30 meshing with the main gear wheel 18 of the coupling member 4. The gear wheels 31 mesh with gear wheels 35 105 on sockets 36 within offset socket members 37 carried by the casings 25. Each socket is held in position by anti-frictional bearings 38, 39 and 40, the last two mentioned bearings cooperating with a collar 41 on the 110 socket 36 as end thrust bearings. A detachable cap or plug 42 permits of the bearings

39 and 40 being easily assembled in the socket member 37 and the socket 36 with the gear wheel 35 and the bearing 38 can be assembled when the casing 25 is detached 5 relative to the housing 9.

The lower portion of the housing 9 is formed with peripheral flanges 43 and the casings 25 are provided with offset bosses 44 having screw bolts 45 and clamping 10 members 33 engaging the flanges 43. As the upper reduced ends of the casings are swiveled in the ends of the housing, it is possible to rotate the casing about the tie rods 27 and thus swing the socket members 15 37 about the casings as an axis. After the casings have been adjusted the screw bolts 45 may be set in fixed engagement with the flanges 43 to lock the end casings and socket members in adjusted positions.

20 The socket members 37 are provided with inverted T-shaped slots 46 and rotatable on the sockets 36 are slotted sleeves 47. These slotted sleeves are provided with pins 48 extending through lateral portions of the 25 slots 46 so that the sleeves 47 may be rotated to register with slots 46^a in the sockets 36, so that a suitable instrument may be driven into said slots to force the tang of a drill 49 from the sockets. The rotatable sleeves 47 permit of the slots being closed to a certain extent to exclude dirt, and other matter that may interfere with the bearings or other parts within the 30 socket members.

35 Connected to the bottom of the housing 9, as at 60, is a central socket member 50 containing a socket 51 articulated with the coupling member 4. The socket 51 is constructed and supported similar to the 40 sockets 36 previously referred to and said socket is adapted to receive a center drill.

In operation, the coupling member 4 im-

parts movement to the gears 18, 30, 31 and 45 35 and during this operation, the various anti-frictional bearings take care of any 45 end thrust to which the end and center drills may be subjected. By loosening the screw bolts 1 the housing 9 may be bodily swung about the coupling member as an axis and by loosening the screw bolts 45 the end casings 50 may be simultaneously adjusted to swing the end socket members in reverse directions, so that end drills may be maintained in the same vertical plane as the center drill, if such drill is used. 55

The preferred embodiment of my invention has been illustrated, but it is to be understood that the structural elements are susceptible to such variations and modifications as fall within the scope of the appended claim. 60

What I claim is:—

A drill head comprising a spindle, a member, a housing attached to said member and provided with openings, supporting members in the openings of said housing, casings extending into the bottom of said housing and supported from said supporting members, drill socket members in said casings, gears adapted to operate said 70 drill socket members from said spindle, and gears on the inner ends of said casings to cause simultaneous adjustment of said casings, anti-frictional bearings in the openings of said housing for some of the gears 75 therein, and anti-frictional bearings in said casings for the drill socket members therein.

In testimony whereof I affix my signature in the presence of two witnesses.

JOSEPH F. BUHR.
